UNITED STATES PATENT OFFICE

EDMUND C. MORGAN, OF RICHMOND HILL, NEW YORK, N. Y.; OLIVE EUGENIE MORGAN EXECUTRIX OF SAID EDMUND C. MORGAN, DECEASED

LOADING MACHINE

Application filed December 8, 1917, Serial No. 206,260. Renewed April 9, 1927.

This invention relates to a machine for loading coal and other material, and is especially adapted for use in mines in which the vein or stratum of coal is very thin so that 5 the roof of the mine chamber opening is very low.

The object of the invention is to provide a machine of the class named which shall be of improved construction and operation.

10 The invention is exemplified in the combination and arrangement of parts shown in the accompanying drawings and described in the following specification, and it is more particularly pointed out in the appended 15 claims.

In the drawings—

Fig. 1 is a horizontal sectional view through a mine chamber showing one embodiment of the present invention in place therein.

20 Fig. 2 is a vertical sectional view of the chamber shown in Fig. 1 and represents the loading machine in elevation.

Figs. 3, 4 and 5 taken together constitute 25 a top plan view of the machine shown in Figs. 1 and 2, but on a larger scale.

Figs. 6, 7 and 8 together constitute a horizontal sectional view of the machine taken 30 on a plane just above the lower portion of the runway for the coal, portions of the machine 35 being broken away to show details of construction.

Figs. 9, 10 and 11 together constitute a side elevation of the machine in place in a mine 40 chamber, parts of the machine being broken away.

Figs. 12, 13 and 14 constitute a vertical sectional view of the machine substantially on line 12—14 of Figs. 3, 4 and 5.

Figs. 15, 16, 17, 18, 19 and 20 are transverse sectional views on lines 15—15, 16—16, 45 17—17 of Fig. 3, 18—18, 19—19 of Fig. 10, and 20—20 of Fig. 5, respectively.

Fig. 21 is a top plan view of a modified form of scoop nose for the machine.

45 Fig. 22 is a vertical sectional view on line 22—22 of Fig. 21.

Fig. 23 is a front elevation, and Fig. 24 a side elevation of still another form of scoop nose; and

50 Figs. 25 and 26 are side and front eleva-

tions, respectively, of a form of door especially designed for use on a car to be loaded by the machine shown in the other figures of the drawings.

While in a great many mines that are being worked at the present time the veins are comparatively thin and the roofs, therefore, low, there are still other veins that are even thinner than those which are now considered as economically workable, and the present invention is designed to operate in such mines with very low roofs; for example, the machine as shown in Figs. 1 and 2, is drawn to a scale of approximately one-quarter of an inch to the foot, so that this machine is represented as working in a mine having a thirty inch vein. In spite of the limited space in which the machine is operated, it is so constructed that ample passageway is provided for the coal, and the parts may be of liberal proportions and substantial construction. The loading machine proper comprises a rear truck A and a forward truck B, the rear truck being arranged to discharge into a car C, while the forward truck carries a scoop D, which is forced beneath the coal by forward movement of the machine in the mine chamber, the coal having been previously blasted down or otherwise loosened in the chamber. The main frame of the rear truck A, as shown in Figs. 3, 6 and 15, comprises a channel-shaped body having a bottom plate 1 and upwardly extending side plates 2 and 3. Secured to the outer faces of each of the side plates 2 and 3 are bracket plates 4 and 5, which are connected with the side plates by inwardly bent portions 6 and 7, respectively, there being a connecting portion at each end of each of the bracket plates, as shown in Figs. 3, 4 and 16. Extending between each of the bracket plates 4 and 5 and their respective side plates, are short axles 8, 9, 10 and 11, on which are rotatably mounted wheels 12, 13, 14 and 15, respectively, which constitute the supporting wheels for the rear truck, and which travel upon the rails 16 of the mine track. A supporting plate 17 extends between the bracket plate 4 and its side plate 2, and upon the plate 17 is mounted a motor 18, shown in Figs. 3, 4, 9, 10 and 17. The motor 18 is provided 100

with a pair of shafts 19 and 20, which are connected by reduction gearing 21 and 22, respectively, with the truck wheels 12 and 13, the wheels being provided with gears 23 and 24 rigidly secured thereto. A pair of transverse shafts 25 and 26 connect the gears 23 and 24 with corresponding gears 27 and 28, secured to the wheels 14 and 15, respectively. By this arrangement rotation of the motor 18 will drive all four of the truck wheels simultaneously in the same direction, thus propelling the machine along the track 16. The direction and speed of rotation of the motor 18 is governed by a controller 29 secured to the bracket member 7, as shown in Figs. 4 and 7.

Connected to the outer face of the side wall 3, between the side wall and bracket member 5, is a second motor 30, provided with a set of reduction gearing contained within the housing 31, and arranged to drive a drum 32, on which cables 33 and 34 are wound. The cables 33 and 34 extend over guide pulleys 35 and 36, respectively, and the end of the cable 33 is connected to projections 37 on one of the cross ties at the rear of the machine, while the cable 34 is similarly connected to a mine jack near the forward end of the machine. The motor 30 is governed by one of a series of controllers 40, supported by the bracket member 6, as shown in Fig. 4. It will be apparent that rotation of the drum 32 in one direction will move the loading machine forward to force the nose of the scoop 38 beneath the material to be mined, while rotation of the drum in the opposite direction will draw the machine rearwardly away from the material. Running-boards 41 and 42 are hinged to the outer faces of the bracket members 4 and 5, respectively, for the accommodation of the operator of the machine. These boards, as will be apparent, may be swung upwardly against the outer faces of their respective bracket plates to permit movement of the machine through narrow passageways, or between the props of a mine.

The forward truck B has a channel-shaped main frame member similar to that of the rear truck A which constitutes the body of the truck, and which is provided with a base plate 43 and side plates 44 and 45, as shown in Figs. 4, 7 and 19. The channel-shaped body portions of the front and rear trucks are pivotally connected with one another, as shown in Figs. 4, 7, 10, 13 and 18, so that the forward truck may swing laterally about the front end of the rear truck. In order to provide this pivotal connection, the forward end of the body portion of the rear truck A is enlarged and given a circular formation, as shown most clearly in Figs. 4 and 7, while the rear end of the forward truck body is similarly shaped. The side plates 2 and 3 of the rear truck body are curved outwardly, as shown at 46 and 47, which outwardly curved

portions embrace similarly curved portions 48 and 49, respectively, of the walls 44 and 45 of the front truck. The bottom plates of each of the truck bodies, between the curved portions of the respective side walls, are extended to form circular portions, the circular portion 50 of the forward truck being arranged to lie upon the circular portion 51 of the rear truck, as shown in Fig. 18. As shown also in this figure, the outer curved walls 46 and 47 of the rear truck are provided respectively with downwardly turned rims or flanges 52 and 53 which overlap the upper edges of the side plates 48 and 49. It will be apparent that this arrangement provides a pivotal connection between the front and rear trucks which permits lateral movement of the front truck body, but holds the two body portions rigid relative to one another in respect to vertical movement. The two circular base plates 50 and 51 may be provided at the central portion with a pivot pin 54, as shown in Fig. 18.

For the purpose of swinging the two truck sections relative to one another, a motor 55, Figs. 4 and 18, is mounted on a downwardly extending portion 56 of the overlapping flange 53 of the curved side plate 47, and is provided with a worm 57, which meshes with a worm wheel 58, carried on a shaft 59, mounted in bearings 60, which are supported from the casing of the motor. The shaft 59 carries a spur gear 61, which meshes with teeth on a rack 62 secured to the inner curved plate 49 of the front truck section. It is apparent that rotation of the motor 55 will cause the body of the front truck to be swung laterally about its pivotal connection with the rear truck. Set screws with hand wheels 63 may be provided for locking the two truck sections against relative movement.

The scoop D is pivotally connected by a hinge 64 to the front end of the body portion of the forward truck, as shown in Figs. 11 and 14. This scoop is also channel-shaped in cross section, as shown in Fig. 20, and is provided with a base plate 65 and side plates 66. As shown in Figs. 5 and 8, the scoop is wider at its forward end than at its rear end, the side walls being arranged to converge inwardly adjacent the connection between the scoop and the main portion of the front truck frame. As will be seen from Fig. 14, the base plate 65 of the scoop D extends only to the hinge 64 where the scoop is connected with the front end of the forward truck. The side members 66, however, are continued along the outside of the truck frame, as shown in Figs. 4, 5 and 10, and constitute lever arms 67, the upper edges of the arms being provided with strengthening flanges 68. A reinforcing plate 69 is secured to the bottom face of the plate 65 in front of the hinge 64, and is provided with shoes 70 which rest on the surface of the mine floor, as shown in Figs. 130

11 and 14. Short axles 71 project from the outer faces of the lever arms 67, and truck wheels 72 are rotatably mounted on these axles and are movable with the arms 67 into 5 and out of engagement with the track rails 16, the two positions of the truck wheels corresponding to the different positions of the scoop D being shown in broken and full lines, respectively, in Fig. 2 of the drawings. The 10 rear ends of the lever arms 67 are provided with socket members 73, in which screws 74 are threaded. The lower ends of the screws 74 are connected with the main frame of the front truck by brackets 75, and by this arrangement 15 the rear ends of the lever arms 67 may be raised or lowered relative to the main frame of the front truck. The screws 74 are provided with operating handles 76 by which they may be rotated. In this way the scoop 20 section D may be elevated or swung into position to rest upon the floor of the mine chamber and support the forward portion of the machine.

From the foregoing description it will be 25 seen that the main frame-work of the machine is channel-shaped throughout its entire length, providing a central conduit through which the coal may be transported from the receiving end of the scoop into position 30 to be discharged into the car C. A pair of conveyor chains 77 and 78 extend the full length of the machine and are arranged so that the inner run of each chain travels rearwardly to convey the coal from the scoop to 35 the car. Extending longitudinally of the central portion of the rear truck A, as shown in Figs. 6, 12, 15, 16 and 17, is a plate 79 secured to the upper surface of the bottom plate 1 of the truck frame by rivets 80. The inner runs of the conveyor chains 77 and 78 slide along the upper surface of this plate and are guided on their inner sides by a spacing plate 81, the outer edges of which fit between the links of the chains 77 and 78, as shown in 40 Fig. 16. The plate 81 is spaced from the upper surface of the plate 79 by spacer strips 82, so that the edges of the plate 18 may overlie the edges of the lower links of the conveyor chains. The outer edges of the inner 45 runs of the chains 77 and 78 are similarly guided by strips 83 spaced upwardly from the plate 79 by spacer strips 84. This construction is also shown in Fig. 6. The strips 84 are of less thickness than the plate 81, so that there is sufficient space between the strips 84 and the upper links of the conveyor chains to permit the edges of plates 85 and 86 to extend beneath the upper links of the conveyor chains. These plates 85 and 86 have upwardly bent side plates 87 and 88, respectively, which are connected to the side plates 2 and 3 of the main frame to the rear truck section. By this construction the plates 81, 85 and 86 are made to constitute the floor for 50 the runway over which the coal is trans- ported, the floor thus formed being provided with longitudinally extending grooves indicated by the numeral 89, in which the inner runs of the conveyor chains are guided, and through which the upper links of the chains 70 extend into position to engage the coal in the runway and cause it to travel rearwardly therein. As shown in the drawings, the chains are not provided with any special projections for engaging the coal, as in most cases, the friction of the chains and the coal is sufficient to cause the coal to travel along the runway. It will be noted that very little elevation of the coal is required throughout its entire travel, and for this reason no positive engaging devices are usually required. If in some cases it is found necessary, the links of the chains may be provided with projections for positively engaging the coal. 55 At their rear ends the chains are directed 85 into their return path by grooves 90, in a block 91 fastened to the upper surface of the plate 1. It will be seen that the chains return between the plate 1 and plates 86 and 87 and the return runs of the chains are on a 90 somewhat lower level than the driving runs. For this reason the grooves 90 are made to slope downwardly toward the outer sides of the machine to bring the return runs of the conveyor into proper level. As will be seen from Fig. 19, the main frame of the front sections is provided with a plate 92, corresponding to the plate 79 of the rear truck section, but of somewhat less thickness. Similarly the inner runs of the conveyor chains 95 are spaced from one another by a plate 93, corresponding to plate 81 of the rear truck, while the return runs of the conveyor are covered by plates 94 and 95, corresponding to plates 85 and 86 of the rear truck. In the 100 central portion of the machine, where the two trucks are pivoted together, the plate 79 has its lower surface cut away, as shown at 96 in Fig. 13 of the drawings, so that the circular portion 50 of the base plate 43 of the 105 front truck section will lie between the circular portion 51 of the rear truck section and the part of the plate 79 not cut away. The part of the plate 79 not cut away has its front corners beveled off, as shown at 97 in Fig. 7, 110 to permit lateral swinging of the front truck, while the central portion of the plate is rounded out upon the line 98 in order to fit a complementary projection 99 extending from the rear end of the plate 92. The spacing plates 81 and 93 are similarly rounded 115 so that their abutting ends fit one another along the line 98, there being a projection 100 on the forward spacing plate 93, corresponding to the projection 99 on the plate 92. The forward ends of the cover plates 85 and 86 for the return runs of the conveyor are rounded off, as shown by broken lines 101 and 102 in Fig. 4 of the drawings, 120 while the rear ends of the cover plates 94 125

- and 95 are similarly rounded, as shown at 103 and 104, the ends of the forward plates overlapping the ends of the rear plates, so that rearwardly moving coal will not catch 5 upon the overlapping edges. The upwardly bent portions 87 and 88 of the cover plates 85 and 86 are extended to a greater height through the central pivotal portion of the machine, as shown at 105 in Fig. 13 of the 10 drawings, so that these extended portions form the side walls for the passageway through this portion of the machine. These upwardly extended walls 105 of the rear truck are not connected with the cover plates 15 85 and 86 through this portion of the machine, as is shown in Fig. 18. This will permit slight lateral springing movement of these walls when the forward truck is swung laterally about its pivotal connection 20 with the rear truck. The cover plates 85 and 86 are extended, as shown at 107 and 108, a slight distance on each side of the runway, so that the side walls 105 will not be moved beyond the edges of the cover 25 plates when they are sprung to one side.
- The conveyor chains 77 and 78 are driven by means of a motor 109, Figs. 4 and 18. The motor 109 is geared to a shaft 110, journaled in brackets 111, extending from the motor 30 casing, and provided with a sprocket wheel 112, over which the outer run of the conveyor 78 passes. The lower end of the shaft 110 is journaled in a bearing 113, which is secured to the plate 51, which, as previously stated, is 35 the circular extension of the main base plate for the rear truck. The motor 109 is mounted upon this same rear truck frame by means of a downwardly extending plate 114 connected with the overlapping edge 52 of the plate 46.
- 40 The lower end of the shaft 110 carries a gear wheel 115, which drives a pair of idlers 116 and 117 mounted on the lower surface of the plate 51, and which in turn drive a gear wheel 118 connected with the lower end of a 45 short shaft 119, journaled in a bearing 120, which extends through the plate 51, the upper end of the shaft being also journaled in the bearing 60. The shaft 119 carries a sprocket wheel 121, which drives the outer run of the 50 conveyor chain 77. The motor 109 is governed by one of the controllers 40 previously mentioned. The gears 115, 116, 117 and 118 are protected by a housing 122 secured to the under surface of the plate 51. The plate 50 55 is provided with arcuate slots 123 through which the bearings 113 and 120 project and in which they slide when the forward truck section is swung laterally relative to the rear section.
- 60 The coal receiving or scoop portion of the machine is provided with a pair of cover plates 124 and 125, corresponding to the cover plates of the two truck sections, and is also provided with a plate 126 on which the active 65 runs of the conveyor chains slide, and also with a spacer plate 127 lying between the two conveyors. Spacer strips for these various plates are also provided, as shown in Fig. 20. The forward end of the scoop section is provided with a nose block 128, which is moved 70 beneath the coal when the machine is fed forwardly, and this block is provided with a rearwardly projecting plate 129 in which grooves 130 are cut for guiding the conveyor chains around their turns at the forward end 75 of the machine. The chains are provided with sufficient slack to permit the lateral movement of the front portion of the machine without unduly stretching the chain. The active runs of the chains will, of course, be 80 kept taut, and the slack will accumulate beneath the cover plates in the scoop section of the machine where there is plenty of space.
- In Figs. 21 and 22, there is shown a modified nosepiece 131, which is provided with 85 rearwardly projecting prongs or horns 132. These horns are for the purpose of breaking up a mass of coal so that it will fall apart and onto the conveyor. It sometimes happens that when a mass of coal is undercut and shot 90 down, although it is shattered by the explosion, it continues to hang together and simply settles slightly in its original position. Under these conditions the mass may be further loosened and caused to fall apart by first 95 forcing the scoop with the form of nosepiece shown in Figs. 21 and 22 beneath the mass by a forward movement of the machine and then drawing the machine back. When this is 100 done the prongs will catch the coal on their rearward movement and by a raking action cause it to fall apart and onto the conveyor.
- Still another form of nosepiece 133 is shown in Figs. 23 and 24 of the drawings. In this form downward projecting ribs 134 105 are secured to the lower face of the nosepiece, and are provided with forwardly projecting chiseling points 135 which serve to break up and loosen any inequalities which may project from the floor of the mine chamber. It should be observed that the spaced-apart chiseling devices 135 are provided with forward bevel surfaces which are inclined 110 upwardly and rearwardly from the floor. The elongated ribs 134 act as skids to slide 115 over the mine floor and because of the reduced area in contact with the floor the friction is minimized. This construction is particularly adapted for operating on semi-compact masses of coal broken down from the face of the mine wall by means of blasting or otherwise. The forward chisel ends 135 will move along the floor and by reason of the bevel surfaces at the forward ends will wedge under 120 the material to be loaded and such material will ride up on the inclined surface 133 into the trough to be acted upon by the conveyor mechanism. The forms of nosepieces shown in Figs. 21, 22 and in Figs. 11, 14 are also provided with beveled surfaces at the forward 125 130

ends so that the bottom of the nosepiece will slide over the floor and the beveled surface will wedge under the material to be loaded and keep the conveyer nosepiece at the floor. 5 It should also be noted that in all of the forms of nosepieces herein disclosed the scooping portion designated D in Figs. 2 and 11 is elongated and quite narrow in thickness. This is desired so that the beveled nose 128 10 may be readily forced under the material at the floor quite a distance while the conveyer chains are being operated to transfer the material toward loading position at the rear end of the trough or channel which extends parallel 15 to the track and very close thereto, as shown in Fig. 2. By providing a flat bottomed elongated scoop with a beveled nosepiece the latter may be readily forced under the material to be loaded and riding up on the material will be prevented. In other words, the construction is such as to assure getting under the coal to be loaded by having the beveled nosepiece 128 act as a wedge to hold the scoop D in close contact with the floor during the scooping operations. 20

It will be seen from Figs. 1, 2 and 12 of the drawings that the discharge end of the loading machine is not elevated to discharge the coal over the side of the car C, but extends 25 through the forward end of the truck. It may be desirable to provide this end of the car with a door which can be opened and closed to permit the insertion of the rear end of the loading machine into the car and to prevent coal from falling out of the car when the machine is no longer in loading position. Such a door is shown in Figs. 25 and 26, and comprises an end gate 136, hinged at 137 to the floor of the car, and provided with articulated side pieces 138, one or both of which may have notches 139 arranged along their curved peripheries. A catch 140 is pivotally mounted on the side of the car for holding the door in either opened or closed position, the closed position being shown in full lines in Fig. 25 of the drawings, while the open position is shown in broken lines.

In operation after the coal has been broken down in any one of the usual ways, the loading machine is run into the mine vein upon the track 15, and the ends of the cables 33 and 34 are secured in fixed position with the forward end of the scoop section D adjacent the broken down coal to be loaded. In the drawings the rear cable is shown as being connected to projections on the cross ties, as previously stated, while the forwardly extending cable is connected to a toggle-jack 141, the legs of which bear against the walls of the mine chamber. Any suitable method for securing the cables may be employed, however. During the movement of the loading machine into the mine chamber, the lever arms 67 are lowered to bring the wheels 72 into engagement with the rails of the track. This position causes the scoop to be elevated, as shown in broken lines in Fig. 2. When the machine is brought to the place where it is to be operated, the screws 74 are rotated to swing the scoop downwardly into engagement with the floor of the mine chamber, and thus shift the weight of the front end of the machine from the truck wheels 72 to the scoop. There will be no great weight upon the scoop, however, or the portion of the machine in the rear of the front axle of the rear truck will counterbalance the greater portion of the weight of the front part of the machine. When the scoop is brought into its operating position, the truck wheels 72 will be raised to clear the track rails, as shown in Fig. 10, so that the scoop may be swung laterally into any desired position. The track itself extends only a very slight distance, usually less than two inches, above the surface of the mine floor, so that the vertical movement of the forward truck wheel is never very great. The motor for driving the conveyor chain may now be started to operate and the machine may be run forward by means of the drum 32 and the cable 34, to force the nose of the scoop beneath the material to be loaded. As fast as the material is brought upon the scoop it will be carried rearwardly through the central portion of the machine by the conveyor chains and deposited in the car at the rear of the machine. The scoop may be fed forwardly in a straight line, as shown in full lines in Fig. 1, and also may be fed forwardly while it is swung to either side of the track, as shown in broken lines in this figure. In this way the material in a chamber of considerable width may be loaded by a single scoop. As the material is fed into the car, the rear portion of the car will first be filled and the car may be moved rearwardly by hand relatively to the machine to cause the material to be distributed in the car, but in most cases this rearward movement of the car will be accomplished automatically by the pressure of the material as it is discharged from the end of the conveyor. It is not desirable to make the action of the conveyor chain upon the material any more positive than is necessary to carry the material to its discharging position, for the reason that the less positive this engagement is, the less danger there is of breaking parts of the machine in case the material becomes choked up. Since there is but very little elevation in the material throughout the entire loading operation, it is not usually necessary to provide any projections upon the conveyor chains for engaging the coal, but of course, such projections may be provided in cases where it is found that they are desirable.

It will be seen that the construction of the machine is such that the material is transferred through the central portion of the machine on practically the same level that the material occupies before it is loaded. The

continuous channel arrangement of the machine without any obstructions over which the material must be lifted, makes such an operation possible, and this method of operation 5 permits the use of the machine in mines where the roof is so low that other forms of machine cannot be used. The arrangement of the supporting wheels and other operating mechanism at the side of the channel permits of the 10 use of operating parts of liberal proportions, so that the machine may be made amply strong in spite of the cramped position in which it is designed to operate. It is apparent 15 from Fig. 2 of the drawings that the machine may be fed forwardly during loading operations until the front wheels of the rear truck come to the forward end of the track. This makes it possible for the machine to work for a long distance in front of the track in the 20 mine chamber.

This loading machine is intended to operate in conjunction with a mining machine substantially like that shown in my co-pending application Serial No. 196,294 filed October 12, 1917. Both machines are track mounted so as to enable them to be quickly moved from one mine chamber to another on a suitable mine track constructed in advance, the preferred plan of operation being as 25 follows; the track is first set in the desired position ending a considerable space back from the mine wall. This work is preferably done by a special gang of men who devote all of their time to this work. The 30 mining machine is next run into the chamber by its set of operatives, and by its novel construction is enabled to undercut the coal face and also drill the blast holes in addition, if desired, doing this work without extending 35 the mine track. After it has completed its operation it is run out of the room on the mine track. All the coal that has been undercut by this operation is then loosened by blasting or other suitable means, a special 40 set of operatives being detailed for this work. The loading machine is then run into the room and performs its operation without any extension of the mine track. The chamber is then ready for the first mentioned gang 45 of men to extend the track for the next operation. All of these operations can be carried on simultaneously in a systematic manner by providing a plurality of mine chambers, enabling a large amount of coal to be mined and 50 transported from the mine with a great saving of labor and concentrating the work so that a comparatively small number of mine chambers are required. By the novel construction of my invention the loading machine 55 is enabled to gather and load substantially all of the coal at the closed end of a mine chamber at one operation, without extending the track, that it is possible for the undercutting machine to undercut at one 60 operation.

I claim:—

1. In a loading machine, the combination with a trough extending in a general horizontal direction and longitudinally to adapt the machine for use in a very low roof mine chamber, of means for supporting such horizontally extending trough with its bottom close to the floor of the mine chamber and substantially parallel thereto, and means for gathering material from a position in advance of said trough and transferring such material along said trough toward the rear delivery end thereof by reciprocating movement rectilinearly of the entire loading machine. 70

2. In a loading machine, the combination with a frame having an elongated conveyer passageway extending horizontally along a mine chamber adjacent the floor thereof, of wheels for supporting said frame for movement over the mine floor, the axes of said wheels being approximately in the plane of the bottom of said passageway so that the latter may occupy such position, and means for effecting the transfer of material longitudinally along such passageway. 80

3. In a loading machine, the combination with a frame having an elongated channel extending horizontally along the central portion thereof, of wheels rotatable on the axes approximately at the bottom of said channel to support the latter close to the ground and with the front and rear portions substantially at the same elevation, and means for propelling the material along said channel while occupying such low positions all the way from the front of the loading machine to the rear end thereof. 90

4. In a loading machine, the combination with a frame having a conveyer conduit extending longitudinally along the central portion thereof, and wheels on opposite sides of said frame with their axles above the bottom thereof to support said conveyer conduit to intersect the axes of said wheels and to support said conveyer conduit to occupy such low position close to the mine floor all the way from the front to the rear end thereof. 100

5. In a loading machine, the combination with a channel-shaped frame having a horizontal longitudinally extending bottom of approximately the width of a mine track, of wheels connected with the outside lateral faces of the upright walls of said frame to support said bottom in a horizontal position extending parallel to the mine track and longitudinally thereof, and means for moving material longitudinally along the channel-shaped frame in lines parallel to said track. 115

6. In a loading machine, the combination of a channel-shaped conveyor frame with the bottom thereof extending in approximately the same horizontal plane throughout its entire length, and wheels located at 120 125 130

- the sides of said frame to support the same on a mine track with the bottom parallel to such track and adjacent thereto with sufficient clearance for said frame to move freely 5 longitudinally of such track.
7. In a loading machine, the combination with a conveyor frame having a channel for the movement of material therethrough, of a jointed connection between sections of said 10 channel, and means for supporting the sections and the jointed connection to maintain the bottom of the channel on substantially the same level across the jointed connection during the various relative positions 15 of said sections.
8. In a loading machine, the combination with a frame having two sections, of connections between said sections to afford adjustment of the forward section laterally to various positions, and means for scooping material into the forward section and transferring such material rearwardly into the rear section and along the latter without changing the level of such section.
- 20 9. In a loading machine, the combination with a conveyor frame having a front and a rear section, of means for connecting said sections to permit the forward section to be adjusted laterally while maintaining a continuous channel passageway from one section to the other, the floor level of said channel passageway being uninterrupted by the connection between said sections or by the adjustment of the forward section to various 25 lateral positions, and means for effecting the introduction of material into the forward section in the various adjusted positions of the latter and movement of such material rearwardly along such channel toward loading 30 position at the rear end of said channel.
- 40 10. In a loading machine, a frame comprising front and rear sections provided with channel-shaped conveyer passageways extending longitudinally thereof, said sections being pivotally connected for lateral movement relative to one another, the channel-shaped passage of each section being arranged to form a continuation of the passage of the other section so that material may be 45 moved on the same level throughout the entire length of said machine.
- 50 11. In a loading machine, the combination with a frame comprising two channel-shaped sections pivotally connected together to form a continuous trough with the forward section laterally adjustable, of means for supporting said sections with the floors thereof in substantially the same horizontal plane, and means for effecting the introduction of material 55 into the forward section and movement rearwardly of such material along such sectional trough to the rear end of the rear section.
- 60 12. In a loading machine, a frame comprising a pair of channel-shaped sections having 65 their adjacent ends pivotally connected with one another for lateral movement and arranged to form a continuous channel with the floor thereof extending in substantially the same horizontal plane throughout its entire length, and wheels connected with the outer sides of said channel-shaped sections for supporting said frame so that the floor of said sections shall be in close proximity to the surface over which said machine operates 70 and below the axes of said wheels.
- 75 13. In a loading machine adapted for operation in very low roof mine chambers, the combination with a wheel supported elongated frame having a trough adapted to 80 travel on a mine track, of a scoop connected to the forward end of said chute and adjusted to positions for scooping material from a space in advance of the mine track and at the sides of such space, means for operating said scoop by moving the same rectilinearly parallel to the track while in any one of its adjusted positions for scooping the material, and means for conveying the scooped material along said trough out of the rear end 85 90 thereof.
- 95 14. In a loading machine adapted for operation in very low roof mine chambers, the combination with a frame having an elongated channel extending in a general horizontal direction longitudinally, of gathering means extending in a general horizontal direction in advance of said channel, means for moving said gathering means rectilinearly to gather a load from the space in advance of said frame, and means traveling along said channel for transferring the gathered material in a general horizontal direction to the rear delivery end of the loading machine.
- 100 15. A machine for loading material in a mine chamber comprising a frame having a passageway extending longitudinally thereof, the floor of said passageway being on substantially the same level throughout its entire length but slightly inclined downwardly at the forward end thereof to permit of the movement of material from the floor of said chamber into said passageway, and chain conveyor mechanism for causing material to be transferred along said passageway and discharged from the rear end thereof into a transporting receptacle.
- 110 16. A machine for loading material in a mine chamber comprising a frame having a channel-shaped passage extending longitudinally therethrough, said frame and passage being provided with a pivotal joint intermediate the ends thereof to permit lateral movement of the opposite ends of said frame relative to one another, the floor of said passage being of the same height throughout the greater portion of the length thereof but slightly inclined downwardly at its forward end to permit movement of material into said passage from the floor of said mine chamber,
- 115 120 125 130

- and a conveyor for transporting material through said frame along said passage and for discharging said material from the rear end of said frame while it remains at substantially the same level to which it was raised by the inclined portion of the front end of said passage.
17. A loading machine comprising a frame having wheels adapted to travel on a mine track, a channel extending longitudinally of said frame with its bottom close to said track, and a scoop pivoted to the forward end of said channel for adjustment laterally while maintaining delivery communication therewith.
18. In a loading machine, the combination with a frame having a trough extending horizontally parallel to a mine track, of wheels for supporting said frame for movement along said track, a scoop flexibly connected to said trough for lateral adjustment thereto while maintaining delivery communication therewith at the elevation of the forward end of said trough, the rear end of said scoop being substantially at the same elevation as the forward end of said trough, and means for operating said scoop and effecting transfer of material from the latter along said trough toward loading position.
19. In a loading machine, the combination with a channel-shaped frame having both ends thereof open, of wheels for supporting said frame with the channel thereof extending longitudinally of said mine track and parallel thereto, a gathering device with its rear end approximately at the elevation of the forward end of said channel for direct registry therewith, a pivotal connection between said gathering device and said frame to permit lateral adjustment of said gathering device while its rear end occupies a position in registry with the forward end of said channel, means for operating said gathering device in its various adjusted positions, and means for effecting the transfer of material from said gathering device through said channel over substantially the same level from the front to the rear end thereof.
20. In combination, a loading machine comprising two sections pivotally connected to swing laterally relative to one another, separate supporting means for each of said sections, and mechanism for moving the supporting means of one of said sections into and out of operative position.
21. In a loading machine, the combination with connecting conveyer sections, of two sets of wheels, one set for supporting the rear conveyer section and the other set for supporting the forward conveyer section on a mine track, and connections between said conveyer sections for supporting the forward conveyer section for horizontal swinging movement to adjusted position when the forward set of wheels are run off the forward end of the mine track.
22. A mining machine comprising a rear section and a front section, connections between said sections to permit lateral movement of the front section relatively to the rear section, wheels for supporting the forward section, and means for moving such wheels out of contact with supporting surfaces to give said front section freedom of lateral movement.
23. A loading machine comprising two sections each having supporting wheels adapted to travel on a mine track, means for swinging one of said sections laterally, and connections for supporting the machine when the forward wheels are run off the forward end of the mine track to permit such swinging of one of said sections laterally.
24. A loading machine comprising a rear section having wheels arranged to run upon a track, a front section pivotally connected with said rear section to swing laterally relative thereto, means for preventing vertical movement of said sections relative to one another, and supporting wheels for said front section movable into position to rest upon said track and movable also out of engagement with said track to permit lateral movement of said front section.
25. In a loading machine, the combination with a conveyor having a material receiving portion, of supporting wheels, and means for moving said receiving portion into position to sustain a portion of the weight of said conveyor and moving said wheels out of supporting position.
26. A loading machine comprising a frame having a material receiving portion movably connected therewith, supporting wheels for said frame, and means for moving said wheels out of operative position when said receiving portion is in position to receive material.
27. In a loading machine, a frame having a material receiving portion movably connected therewith, supporting wheels for said frame, and means for moving said material receiving portion into contact with a surface from which material is to be loaded and for lifting said wheels free from said surface.
28. In a loading machine, a frame having a laterally swinging portion thereon, a receiver for material movably connected with said laterally swinging portion, supporting means for said laterally swinging portion, means for moving said receiver into contact with a surface from which material is to be loaded, and means for holding said supporting means free from said surface when said receiver is in contact therewith.
29. In a loading machine, a frame having a laterally swinging portion, a vertically movable receiver connected with said laterally swinging portion, supporting wheels for said laterally swinging portion, and mecha-

nism for moving said receiver into engagement with a surface from which material is to be loaded and for simultaneously lifting said supporting wheels free from said surface 5 to prevent said wheels from interfering with the lateral swinging movement. 70

30. In a loading machine, a frame, a receiver for material to be loaded pivotally connected with said frame for vertical movement relative thereto, arms connected with said receiver, and wheels mounted on said arms on the side of said pivotal connection away from said receiver so that said wheels are moved upwardly out of engagement with 10 the supporting surface for said machine when said receiver is moved downwardly into engagement with said surface. 75

31. In a loading machine, a conveyor having a horizontally projecting portion, a receiver for said conveyor pivotally mounted at the end of said portion and having arms extending rearwardly of the pivotal connection between said receiver and said conveyor, and supporting wheels for said conveyor carried 20 by said arms and movable into and out of contact with the surface upon which said conveyor is supported. 80

32. In a loading machine, a conveyor having a forwardly projecting portion, means for swinging said portion laterally, a receiver for said conveyor pivotally mounted at the end of said projecting portion, arms connected with said receiver and extending in the rear of the pivotal connection between 35 said receiver and said conveyor, and wheels for supporting said conveyor carried by said arms and movable into supporting position when said receiver is raised out of operative position and movable out of such position 40 and free from the surface on which said conveyor is supported when said receiver is in operative position to prevent said wheels from interfering with the lateral movement of said projecting section. 100

33. In a loading machine, a frame, arms pivotally mounted on said frame, a receiver for material carried by said arms and projecting beyond said frame, wheels mounted on said arms adjacent said frame, and means 50 for tilting said arms to alternately bring said receiver and said wheels into position to support a portion of the weight of said frame. 110

34. In a loading machine, a conveyor frame having a forwardly projecting channel-shaped portion, arms pivotally mounted at the end of said conveyor, a receiver for material carried by said arms in front of said conveyor, wheels carried by said arms adjacent the projecting portion of said conveyor, and 55 screws for tilting said arms about their pivotal connection with said conveyor to raise said receiver free from the surface upon which said machine is operated and to bring said wheels to bear upon said surface to support said conveyor when said arms are in one 115

position and to swing said arms into a second position in which said receiver rests upon the surface from which material is to be loaded and in which said wheels are free from said surface to permit lateral movement of said conveyor. 120

35. In a loading machine, the combination with a channel-shaped conveyor section, of supporting wheels connected to the outer lateral faces of said section to support the channel with its bottom adjacent the surface on which the wheels are adapted to travel, a motor, propelling mechanism between said motor and said wheels, and means for supporting said motor adjacent one of said lateral faces at one side of the channel. 125

36. In a loading machine, a frame comprising a channel-shaped conveyor section, means for supporting said frame with the bottom of said channel-shaped section adjacent the surface over which said machine operates, brackets connected with the outer lateral faces of said channel section, supporting wheels for said frame journaled in said brackets, and a motor for operating said machine, supported by one of said brackets adjacent the outer lateral face of said channel-shaped section. 130

37. In a loading machine, a frame comprising a channel-shaped conveyor section, wheels for supporting said frame connected with said channel-shaped section adjacent opposite outer lateral faces thereof, a motor positioned adjacent one of said lateral faces for driving said wheels, and means extending beneath said channel-shaped conveyor section for causing the wheels at opposite sides of said section to move in unison with one another. 140

38. In a loading machine, a frame comprising a channel-shaped conveyor section, a bracket connected with an outer lateral face of said section, a pair of wheels journaled in said bracket, a motor supported between said bracket and said conveyor section, gearing for driving said wheels from said motor, a second bracket connected with said conveyor section on the side thereof opposite the first-mentioned bracket, wheels journaled in said second bracket, and means extending beneath said conveyor section for driving said last-mentioned wheels from said motor. 150

39. In a loading machine, a frame comprising a channel-shaped conveyor section, brackets connected with opposite lateral faces of said conveyor section, wheels positioned adjacent the lateral faces of said conveyor section for supporting said frame, a motor supported by one of said brackets for driving said wheels, a drum support adjacent the side of said conveyor section opposite said first-mentioned motor, a second motor for driving said drum, and cables arranged to be wound on said drum to shift the position of said machine. 160

40. In a loading machine, the combination 130

with a channel-shaped conveyer trough, of a pair of conveyer chains each having the rearwardly traveling run thereof arranged to move along the bottom of said trough intermediate the sides thereof in exposed position to carry material directly thereon, mechanism covering the return runs of said conveyer chains to prevent contact between said return runs and the material to be loaded, and means for driving said chains with the pivotal axes between the links thereof in upright positions.

41. In a loading machine, the combination with a channel-shaped runway for material to be loaded, of a conveyer chain mounted to travel rearwardly along said runway with its pivotal connections between links on upright axes and in exposed position for receiving material in direct contact therewith, a plate for covering the return run of said chain to prevent contact between said return run and the material being loaded, and means for driving said chain to convey such material rearwardly along said runway.

42. In a loading machine, the combination with a conveyer channel, of a conveyer chain, means for guiding said conveyer chain to travel along said channel intermediate the sides thereof and with the pivotal connections between the links of said chain in upright position and exposed for receiving the material to be loaded in direct contact therewith to be carried and dragged along said channel, and means for driving said conveyer chain to travel along said channel rearwardly from the front toward the rear to convey such material along said channel.

43. In a loading machine, a horizontally extending passageway for material to be loaded, a pair of conveyor chains each having an inner run and an outer run supported in said passageway, a guide plate extending between the inner runs of said chain for supporting material and for guiding said runs, and cover plates having their inner edges arranged adjacent the path of travel of said inner runs and extending over the outer runs of said chains for preventing contact between said outer runs and material to be loaded.

44. In a loading machine, a passageway for material to be loaded, a pair of conveyor chains for moving material through said passageway, plates for supporting the material in said passageway, supports for said plates arranged to hold said plates in position to form guide channels for the forward runs of said conveyor chains and to cause said plates to lie above the return runs of said chains to prevent material from contacting with the return runs.

45. In a loading machine, the combination with a pair of trough-shaped channel sections having the abutting ends open and registering with each other to permit free passage of material from one section to the other, of a

pivotal connection between the abutting ends of the channel sections to permit lateral movement of said sections relatively to each other, means for supporting said channel sections to maintain delivery communication between them for the various lateral adjustments of said channel sections, and means for effecting the gathering of material in the forward section in its adjusted position and transferring such material along said channel sections to the rear end of the loading machine.

46. In loading apparatus, the combination with a pair of channel-shaped conveyer sections arranged end to end to form a trough for the passage of material, of curved walls at the abutting end of said trough sections, a pivotal connection between said trough sections to permit relative lateral movement of such trough sections while delivery communication is maintained between said sections, and endless chain conveyer mechanism for transferring material along said trough while said sections are in relatively adjusted positions.

47. In a loading machine, the combination with a pair of channel-shaped sections arranged end to end, the floors of said sections at the abutting ends thereof being arranged in circular formation and placed so that the floor of one section rests upon the floor of the other section, the walls of said sections being curved to correspond to the contour of the curved portions of the floor thereof and engaging one another to form a pivotal connection between said sections, of means for moving said sections to cause the forward section to gather a load of material, and means for transferring the gathered material along said channel-shaped sections toward loading positions.

48. In a loading machine, a pair of channel-shaped conveyor sections arranged end to end with the end of one section telescoped in the end of the other of said sections, the telescoped portions of said sections being curved outwardly at each side thereof to form a pivotal connection between said sections.

49. In a loading machine, a pair of channel-shaped frame members, the end of one of said members extending into the end of the other, said interfitting ends having the walls thereof curved outwardly to permit lateral movement of one of said sections relative to the other, and means for moving material from one of said sections to the other through said interfitting portions of said frame members.

50. In a loading machine, the combination with conveyor sections pivotally connected together, with the forward section adjustable laterally relatively to the rear section, of means for locking said sections in such relatively adjusted positions, and means for moving the forward section rectilinearly for the purpose of gathering a load of material.

51. In a loading machine, a pair of channel-shaped frame members having the ends thereof arranged to interfit with one another and having the side walls thereof curved outwardly to form a pivotal connection between said members, and supplementary side walls adjacent the outwardly curved portions of said main side walls and forming a continuation of the straight portions of said main side walls past the interfitting portions of said frame members. of the sides of one of said members being bent over the upper edges of the corresponding sides of the other of said members to prevent vertical movement relative to one another, and means for shifting said members laterally about their pivotal connection with one another. 70
52. In a loading machine, a pair of channel-shaped frame members having the end of one of said members extending within the end of the other, the overlapping walls of said members being curved outwardly to form a pivotal connection between said members, and operating mechanism for said machine located within the pocket formed by the outwardly curved portion of said walls. 75
53. In a loading machine, a pair of channel-shaped frame members arranged end to end and having the adjacent ends thereof telescoped one within the other, the overlapping portions of the side walls of said members being curved outwardly to form a pivotal connection between said members, supplemental side walls arranged adjacent the outwardly curved portions of said main side walls to 80 form a continuation of the main channel of said frame members, and a motor for operating said loading machine located within the pocket formed by one of said supplemental walls and the outwardly curved portions of 85 said side walls. 90
54. In a loading machine, a pair of channel-shaped frame members arranged end to end with the end of one of said members extending into the end of the other, the overlapping portions of the walls of said members being curved outwardly to permit lateral swinging movement of said members relative to one another, and a motor supported by one of said frame members and having a driving connection with the other of said members for moving said members relative to one another about their pivotal connection. 95
55. A loading machine comprising a pair of channel-shaped frame members having adjacent ends thereof fitting one within the other, the interfitting portions of said members being curved to permit pivotal movement of said members relative to one another, a motor connected with one of said members, and a rack and pinion connection between said motor and the other of said members whereby said members may be moved relative to one another about their pivotal connection by operation of said motor. 100
56. In a loading machine, a pair of channel-shaped frame members having adjacent ends thereof extending one within the other, the overlapping sides of said members being curved outwardly to form a pivotal connection between said members, the upper edges 105 of the sides of one of said members being bent over the upper edges of the corresponding sides of the other of said members to prevent vertical movement relative to one another, and means for shifting said members laterally about their pivotal connection with one another. 110
57. In a loading machine, a pair of channel-shaped frame members having adjacent ends thereof extending one within the other so that the bottom plate of one of said members rests upon the bottom plate of the other and the side walls of said first-mentioned member extend within the side walls of said second-mentioned member, said side walls being curved outwardly to permit lateral pivotal movement of said members relative to one another, the upper edges of the side walls of one of said members being turned over the upper edges of the side walls of the other of 115 said members to prevent vertical movement of said members relative to one another, a motor carried by one of said members in the space included in the outwardly curved portion of said side walls, and mechanism operated by said motor for shifting said members relative to one another. 120
58. In a loading machine, a pair of channel-shaped frame members having adjacent ends thereof extending one into the other, the interfitting portions of said members being arcuate-shaped to permit lateral movement of said members relative to one another, conveyor mechanism located within said channel-shaped frame members and extending through the interfitting portions thereof, material supporting plates connected with said conveyor mechanism, said plates being provided with a jointed connection within the overlapping portions of said frame members 125 to permit lateral movement about the pivotal axis of said frame members. 130
59. In a loading machine, the combination with a pair of channel-shaped frame members pivotally connected together for relative swinging movement on an upright axis, of arcuate guiding mechanism concentric with such upright axis and connected to said channel-shaped frame members in position to maintain delivery communication between such channel-shaped frame members, conveyor mechanism extending along the channel formed by said frame members and beyond the pivotal connection between such members, guides for said conveyor mechanism mounted on said frame members, and mechanism for enabling the guides to register adjacent the pivotal connection between said frame members when the latter are in their various relatively adjusted positions. 135
60. In a loading machine, a pair of channel-shaped frame members arranged end to end with one another, the abutting ends of said frame members extending one within the other and having their side walls curved 140

outwardly to form a pivotal connection between said members and having their bottom portions overlapping, a conveyor chain extending through the overlapping portions of said frame members, and a motor for driving said chain having a shaft journaled in the bottom portion of one of said frame members and extending through an arcuate slot in the bottom portion of the other of said frame members.

61. In a loading machine, a pair of channel-shaped frame members arranged end to end with one another with the end of one of said members extending into the end of the other of said members, the overlapping portions of said members being of an arcuate shape to permit lateral swinging movement of one of said members relative to the other, a pair of conveyor chains extending through the overlapping portions of said members, a motor connected with one of said members and having a sprocket wheel for driving one of said conveyor chains, a sprocket wheel for driving the other of said chains, and gearing for connecting said last-mentioned sprocket wheel with said motor.

62. In a loading machine, a pair of channel-shaped frame members having adjacent ends thereof interfitted with one another to form a pivotal connection between said members, plates arranged to form a runway for material to guide said material through the interfitting portions of said frame members, said plates having jointed connections with one another to permit of lateral swinging of said frame members, a motor located at one side of said runway, a conveyor chain driven by said motor and extending through said runway, a second conveyor chain having one run thereof located at the side of said runway opposite said motor, and gearing extending beneath said runway and connected with said motor for driving said last-mentioned conveyor chain.

63. In a loading machine, a pair of channel-shaped frame members having adjacent ends thereof extending one within the other, the overlapping portions of the walls of said channel members being curved outwardly to form a pivotal connection between said members, and supplementary walls arranged to form a passageway through the overlapping portions of said frame members, said supplementary walls being provided with overlapping resilient portions for permitting lateral movement of said frame members relative to one another.

64. In a loading machine, a pair of channel-shaped frame members having adjacent ends thereof extending one within the other, the overlapping walls of said members being curved outwardly to form a pivotal connection between said members, a pair of conveyor chains extending through the interfitting portions of said members, supplementary side

walls for forming a passageway through said interfitting portions, said supplementary walls having overlapping resilient members to permit lateral swinging of said channel-shaped frame members, a motor located at one side of said passageway and within the outwardly curved portions of the walls of said frame members and connected with said conveyor chain for driving the same, and a second motor located at the opposite side of said passageway and within the outwardly curved portions of the walls of said frame members and connected with said frame members for swinging them upon their pivotal connection with one another.

65. A loading machine for picking up loosened material in the closed end of a mine chamber and transferring said material to a receptacle for transportation out of the mine comprising a scoop body, an elongated frame to which said scoop body is attached and which acts as a handle for said scoop body, track wheels on said frame, a track on which said wheels and frame travel, means for locking said scoop body against lateral movement with respect to said elongated frame, endless conveyer mechanism extending from the front end of said scoop to the rear end of said elongated frame, and means independent of said track wheels for bodily moving the said elongated frame and said scoop on a line parallel with said track to move said scoop beneath said loosened material.

66. Loading apparatus for picking up loosened material in the closed end of a mine chamber and transferring said material to a receptacle for transportation out of the mine comprising a power-operated unitary structure, said unitary structure including a scoop body, an elongated frame attached to said scoop body and operating as a handle therefor, track wheels on said elongated frame, a track for said wheels, said scoop extending forwardly of said elongated frame and adjustable laterally thereon, means for preventing lateral movement of said scoop on said frame when so adjusted, endless conveying mechanism extending from the front of said scoop to the rear of said elongated frame and arranged for lateral adjustment to correspond with the lateral adjustment of said scoop, and means for bodily moving said elongated frame and said scoop on a line parallel with said track to move said scoop under said loosened material.

67. In a loading machine, the combination with a wheel mounted supporting frame adapted to travel on a mine track, of a channel mounted on said frame to extend horizontally thereof, a forwardly extending elongated scoop having its rear end in registry with the forward end of said channel and having a flat bottom adapted to slide over the mine floor with its forward edge beveled to wedge under and scoop up material to be

- loaded, conveyer mechanism extending from said beveled end to the rear end of said channel, a pivotal connection between said scoop and said channel to permit said scoop to be 5 adjusted laterally relatively to said channel, and means for bodily advancing and retracting the entire machine on said track to give said scoop while in various laterally adjusted positions a series of forward and backward strokes along the floor of the mine chamber 10 in advance of the mine track and at the sides of the space in advance of the mine track to gather and load dislodged material.
68. In a machine for loading material in 15 very low roof mines by gathering substantially all of the loosened material on the floor at the closed end of a mine chamber and transferring it rearward and depositing it into a portable receptacle depending for its principle of action on a plurality of bodily movements of the entire machine forward and back in a rectilinear path, the combination with two substantially horizontal trough-like frames arranged in tandem and pivoted 20 together by means of a vertical pivot, the whole to form an unobstructed passageway from the front of the forward frame to the rear of the rearward frame and open at both ends, of a receiving lip at the forward end of 25 the forward frame arranged for vertical adjustment with respect to the rearward frame, a plurality of side wheels adapted to run on a track, a conveyer extending from a position near the forward end of the forward 30 frame to the rear end of the rearward frame, means for operating said conveyer mechanism, means for swinging the forward frame laterally with respect to the rear frame, means for vertically adjusting the said receiving lip, 35 and means for reciprocating the machine bodily.
69. In loading apparatus for low roof mines, the combination with two substantially horizontal trough-like frames arranged 40 in tandem and pivotally connected together, of wheels for said frames having axes all of which are above the bottom of the said trough-like frames, the latter forming an unobstructed passageway from the front of the forward 45 frame to the rear of the rearward frame through the space between said wheels, a scoop extending in advance of the forward frame and having a receiving lip vertically adjustable, conveyer mechanism extending 50 from a position back of and near the receiving lip to a position at the rear end of the rear frame, means for operating said conveyer mechanism, means for swinging the forward frame together with said scoop laterally, means for vertically adjusting said receiving lip, and means for reciprocating the machine bodily to secure rectilinear scooping 55 movements of said scoop rectilinearly and parallel to the track.
70. In loading apparatus for low roof 60 mines, the combination with a longitudinal frame, of wheels for supporting said frame and adapted to run on a track, a channel extending longitudinally of said frame with its bottom in a plane below the axes of said mounting wheels throughout the length of 65 said chute, a scoop connected to the forward end of said frame with its rear open end in registry with the forward end of said channel, conveyer mechanism for transferring material from the forward portion of said scoop backwardly through the open rear end thereof and along said channel to the rear open end of the latter, means for adjusting the scoop laterally, and mechanism for reciprocating the entire machine bodily to effect rectilinear strokes of said scoop parallel to the track in the various lateral positions of said scoop.
71. In a loading machine for low roof 70 mines, the combination with a frame, mounting wheels for the forward portion of said frame and mounting wheels for the rear portion of said frame, said mounting wheels being adapted to run on a track, a channel having open ends and extending longitudinally of said frame substantially parallel to the track, a scoop connected to the forward end of said frame and extending in advance thereof, and means for operating said scoop by moving the entire machine forward with the front wheels out of engagement with the track.
72. In a loading machine for low roof 75 mines, the combination with a frame comprising two sections intermediately pivoted together for lateral movement while being confined against relative vertical movement, of track wheels for the forward section, additional track wheels for the rearward section, a scoop connected to the forward section and extending in advance thereof, a chute extending rearwardly from said scoop longitudinally of said sectional frame, and means for reciprocating the machine to move 80 said scoop rectilinearly parallel to the track in its various laterally adjusted positions.
73. In a loading machine for low roof 85 mines, the combination with frame-work comprising two sections pivotally connected together, of track wheels for the forward section, additional track wheels extending downwardly from the rear section, said track wheels being adapted to run on the same track for supporting the machine for transportation, a scoop for the forward section, means for reciprocating the frame-work with the forward track wheels out of engagement with the track while the machine is still supported on the rear track wheels, and a channel extending longitudinally of said frame-work back of said scoop.
74. In a loading machine for low roof 90 mines, the combination with a frame having three sections in tandem, the intermediate 95

section being pivoted to the rear section for lateral movement relatively to the latter while confined against relative vertical movement and the forward section being pivoted to said intermediate section for vertical movement relatively thereto while being confined against lateral movement relatively thereto, of a scooping lip at the forward end of the forward section, track wheels for the intermediate section, additional track wheels for the rear section, both sets of track wheels being adapted to run on the same track while said intermediate section and forward section are maintained in tandem with said rear section, a channel extending from said receiving lip longitudinally of said frame to the rear end of said rear section in a general horizontal direction between the wheels on one side of said frame and the wheels on the other side thereof, conveyer mechanism having rearwardly moving portions located on each side of the longitudinal center of said channel, and means for reciprocating the machine to secure rectilinear motion of the receiving lip parallel to the track while the forward section of said frame is in various laterally adjusted positions.

75. In a loading machine, the combination of a frame, of wheels for said frame extending downwardly from the same for running on a track to support said frame, of a conveyer extending from the rear portion of said frame forwardly in advance thereof to a position on the floor in advance of the end of the track while said wheels are spaced a substantial distance back from such end of the track, a scoop connected to the forward end of said frame and having a receiving lip in advance of said conveyer, and propelling mechanism for the machine to move said receiving lip over the ground in advance of said track to scoop up material and direct it onto said conveyer for transfer longitudinally to said frame to the rear portion thereof back of said wheels and for loading into a mine car on said track back of the machine.

76. In a loading machine, the combination with a plurality of spaced-apart trucks adapted to travel on a mine track, of framework comprising a plurality of horizontally extending sections one section supported on each of said trucks respectively, conveyer channels, one extending along each of said sections and arranged end to end in registry with each other with their bottoms approximately at the axes of the wheels of said trucks to adapt said channels for use in very low roof mine chambers, and traveling conveyor mechanism extending longitudinally of said framework and of said track along said channels from the front to the rear.

77. A loading machine comprising gathering and loading mechanism, a pair of spaced-apart trucks one for the gathering mechanism and the other for the loading

mechanism, and a pivotal connection between the gathering mechanism and the loading mechanism permitting relative lateral movement but confining them against relative vertical movement.

70

78. A loading machine comprising gathering and loading mechanism, a pair of spaced-apart wheel trucks one for supporting the gathering mechanism and the other for supporting the loading mechanism and both adapted to travel on a mine track, and means for supporting one of said trucks free from said mine track.

75

79. In a loading machine, the combination with conveyer mechanism, of framework for said conveyer mechanism, said framework comprising two sections pivotally connected together for relative lateral movement while being confined against relative vertical movement, track wheels extending downwardly from the forward section, additional track wheels extending downwardly from the rear section in position to support the entire machine when the forward wheels are moved to a position beyond the ends of the track on which the machine is mounted, and means at the pivotal connections between said sections for supporting the forward track wheels up off the floor when moved along the ends of said track.

80

80. In a loading machine, the combination with a frame, of wheels extending downwardly therefrom and adapted to run on a track, a conveyer mounted on said track and extending longitudinally thereof, and means for adjusting said conveyer to support the same free from said track during transportation of said machine, said means being arranged to swing said conveyer downwardly into contact with a supporting surface to transfer a portion of the weight of said frame from said wheels to said conveyer independently of the wheels.

95

81. In a loading machine, the combination with a sectional frame, of a pivotal connection between the sections of said frame to permit relative lateral movement of the forward section, a truck for the rear section adapted to run on a track on the ground, an additional truck for the forward section adapted to run on the same track, a conveyer extending longitudinally of said sections, a receiving device connected in advance of the forward section, means for letting down the said receiving device and lifting the forward truck off the track to permit lateral movement of said forward section and said receiving device, and propelling mechanism for the machine to effect rectilinear motion of said receiving device parallel to the track.

100

82. In a loading machine, the combination with material-handling mechanism, of a pair of trucks for supporting said mechanism, and means for supporting one of said trucks and said mechanism on the other truck.

125

130

83. In a loading machine, the combination with conveyer mechanism comprising a front section and a rear section pivotally connected to permit movement of the front section relatively to the rear section, of a pair of trucks for supporting said conveyer mechanism, means carried by the forward section for swinging the receiving end of the conveyer vertically, and means for supporting the forward truck with its wheels off the track on which the trucks run and also off the ground in advance of the track. 70
84. In a loading machine, the combination with a portable frame comprising three sections in tandem, the forward section being pivotally connected to the intermediate section on a substantially horizontal axis and the intermediate section being pivotally connected to the rear section on an upright axis, of conveyer mechanism extending longitudinally of said sections from the front portion of said frame toward the rear thereof, means for swinging the forward section upwardly for transportation of the machine and downwardly into contact with the ground to assist in supporting said frame during the operation of said machine, and mechanism for swinging the intermediate section laterally relatively to the rear section to adjust the position of the forward receiving section of said conveyer mechanism. 75
85. A loading machine comprising material handling mechanism having front and rear sections, a pivotal connection between said sections to permit relative movement thereof on an upright axis, a pair of trucks one for each of said sections, means for locking said sections against relatively lateral movement, and means for operating said material handling mechanism to gather material by rectilinear movement. 90
86. In a loading machine, the combination with a scoop, of a channel directly back of said scoop and adjustable to be horizontally in alinement therewith to occupy a very low position for movement along a very low roof mine chamber, means for moving said scoop forward to take a load, and a conveyor comprising links having vertical axes and traveling along said channel. 100
87. In a loading machine, the combination with a scoop, of means for reciprocating said scoop, mechanism for adjusting the forward end of said scoop, a channel extending horizontally back of said scoop and in alinement therewith, and a chain with links having pivots on vertical axes traveling along said channel toward loading position and having a return run in an approximately horizontal plane of the channel run. 110
88. In a loading machine, the combination with a truck adapted to travel on a mine track, of a narrow elongated frame comprising a channel having a bottom approximately in the plane of the axes of the wheels of the truck and extending parallel to the mine track, a scoop open at its rear end to register with the forward open end of said scoop in a position adjacent the track, means for reciprocating said scoop to take a load from a mine floor in advance of the track and direct such material toward said channel, and a conveyer traveling from said scoop along the bottom of said channel toward loading position at the rear end of said channel. 120
89. In a loading machine, the combination with a conveyer channel, of a scoop open at its rear end and registering with the forward open end of said conveyer channel, means for moving said scoop bodily forward to take a load of material, and a pair of chain conveyers each with its links pivoted together on upright axes and having the rearwardly traveling runs guided along the free and unobstructed passageway extending along said channel between the sides thereof to move the gathered material along such channel toward loading position. 125
90. In a loading machine, the combination with a conveyer channel having a free and unobstructed passageway from end to end between the inner sides thereof, of a scoop open at its rear end and registering with the forward open end of said channel, means for moving said scoop forward to gather a load, and conveyer mechanism comprising an endless chain having upright pivots and an operating run extending along the bottom of said channel spaced from both inner sides thereof in position to directly engage the gathered material and move the same to the rear open end of said channel. 130
91. In a loading machine, the combination with a main frame, of a supplemental frame pivotally connected to said main frame for lateral movement, a scoop connected to said supplemental frame and extending in advance thereof, means for moving said scoop rectilinearly to reach forward for loads in various arcuate positions, a conveyer channel back of said scoop, said conveyer channel having a free and unobstructed passageway from end to end between the inner side walls thereof and having its forward open end in registry with the rear open end of said scoop, and conveyer mechanism comprising a chain with upright pivots between the links and mounted to have an operating run along the bottom of said channel spaced from the inner side walls thereof in position to come in direct contact with the material gathered by said scoop and move such material to the rear open end of said channel. 140
92. In a loading machine, the combination with a conveyer channel having a free and unobstructed passageway between the inner side walls thereof, conveyer mechanism comprising a plurality of chain runs extending along the bottom of said channel and distributed between the inner side walls thereof. 145

by being spaced apart and spaced from such walls, and means at the forward end of said channel for gathering material from the floor for said conveyer mechanism.

- 5 93. In a loading machine, the combination with a main frame, of a supplemental frame pivoted on said main frame for lateral movement on an upright axis, a scoop pivotally connected to said supplemental frame on a 10 transverse axis and extending horizontally in advance of said supplemental and main frames, a channel mounted on said main frame to extend longitudinally thereof in a general horizontal direction from the front 15 portion thereof to the rear, said channel being open at both ends and having its forward end in registry with the rear open end of said scoop when material is transferred from said scoop to said channel, mechanism for moving 20 said scoop forward along horizontal lines parallel to the length of the main frame and of said channel and while said scoop occupies its various angular positions to gather material in advance of said frames, and an end- 25 less chain conveyor having its links pivoted together on vertical axes and traveling along said channel to move material therein toward loading position.

94. In a loading machine, the combination 30 with an elongated main frame, of a supplemental frame pivotally connected to said main frame for lateral movement, a scoop connected to said supplemental frame and movable laterally therewith, an elongated 35 horizontal channel back of said scoop and in horizontal alignment therewith to extend longitudinally of said main frame from the front toward the rear thereof to clear a very low roof in a mine chamber, propelling 40 mechanism for moving said frames forward to force said scoop into material to be loaded, and an endless chain comprising links pivoted together on vertical axes with one of the 45 runs of said chain continuously traveling along said chute to transfer material toward loading position.

95. In a loading machine, the combination 50 with a frame having a forward longitudinal extension, of wheels extending downwardly from the rear portion of said frame to support the latter on a track, a scoop pivotally connected to the forward portion of said extension on a transverse axis for vertical adjustment, spaced-apart rearward extensions 55 from said scoop, wheels mounted on said rearward extensions, means for adjusting the elevation of said rearward extensions to lift said scoop off the ground and move the wheels 60 of said rearward extensions into contact with the track for transportation and moving said scoop downwardly with the wheels of said rearward extensions off the track, and conveyer mechanism extending longitudinally 65 of said frame for transferring toward load-

ing position the material directed by said scoop onto said conveyer mechanism.

96. In a loading machine, the combination with a main frame, of a supplemental frame pivoted on an upright axis on said main frame, wheels extending downwardly from said main frame and adapted to run on a track for supporting said main and supplemental frames, endless conveyer mechanism extending from a forward position in a plane below 70 all of the axes of said wheels when in receiving position, a scoop having its forward receiving lip always in advance of said conveyer mechanism when in scooping position and always in advance of said frames when in 75 scooping position, said scoop being mounted on said supplemental frame while confined against lateral movement relatively to said conveyer mechanism, the forward receiving lip of said scoop being movable up and down 80 on a horizontal transverse axis, such movement being limited to arcs less than a complete circle, means for operating said conveyer mechanism to transfer material longitudinally of said supplemental frame toward 85 loading position, propelling mechanism connected to said wheels, and additional propelling mechanism independent of said wheels and adapted to be connected between 90 the machine and an anchor in the mine to 95 secure more powerful movement of said scoop forwardly to take a load.

97. In a loading machine, the combination with a frame mounted on wheels with a plurality of transverse axes, of a supplemental 100 frame pivoted to said main frame for lateral movement relatively thereof, endless conveyer mechanism extending longitudinally of said supplemental frame from a forward receiving position toward the rear, said conveyer mechanism having its forward end always in a horizontal plane below the axes of said wheels when in receiving position, a scoop pivotally connected to said supplemental frame to move laterally therewith but 105 confined against lateral movement relatively to said conveyer mechanism, such pivotal connection between said scoop and said supplemental frame enabling the receiving lip of said scoop to be moved up and down on a horizontal transverse axis, such movement being limited to arcs less than a circle, said scoop being connected to said supplemental frame 110 so as to always extend in advance of said main and supplemental frames when in receiving position, propelling mechanism connected to said wheels, means for controlling the operation of said propelling mechanism at will, additional propelling mechanism carried by the machine and operating independently of the wheels and adapted to be connected between the main frame and an anchor in the mine to force said scoop under material 115 to be loaded, and means for controlling the 120 operation of said additional propelling mechanism. 125

operation of said additional propelling mechanism.

98. In a loading machine, the combination with a main frame, of a supplemental frame 5 pivotally connected to said main frame for lateral movement relatively thereto, and a scoop mounted on said supplemental frame in advance thereof and having a scooping nose extending in an arc concentric with the pivot 10 of said supplemental frame on said main frame.

99. In a loading machine, the combination with a track-mounted frame, of a scoop mounted thereon for lateral movement, conveyor 15 mechanism for receiving material from said scoop and conveying it longitudinally of said frame toward the rear, mechanism on one side of the machine for swinging the scoop laterally, and mechanism on the other side of 20 the machine for operating the conveyor mechanism.

100. In a loading machine, the combination with a frame, of downwardly extending 25 wheels for supporting said frame on a track, material-gathering and conveying mechanism mounted on said frame and extending longitudinally thereof to loading position back of said frame, motor propelling mechanism on one side of the machine connected to the 30 wheels on the track, additional propelling mechanism adapted to be connected to anchoring means in the mine, and a motor on the other side of the machine connected to said additional propelling mechanism.

35 101. In a loading machine, the combination with a frame, a plurality of wheels for supporting said frame on the track, a scoop movably connected to the forward end of said frame to extend in advance thereof, spaced-apart arms extending back from said 40 scoop, a pair of wheels connected to said arms and spaced apart in accordance with the track gauge, means for lifting the wheels of said arms off the track when the scoop is lowered to receiving position, and conveyor 45 mechanism extending longitudinally of said frame and through the space between the upright planes of said arms and the wheels thereof.

50 102. In a loading machine, the combination with a track-mounted frame, of a scoop mounted thereon and extending in advance thereof and laterally adjustable, and propelling mechanism independent of the wheels of 55 said track-mounted frame and adapted to be connected to anchoring means forwardly and rearwardly to effect reciprocation of the entire machine to move the scoop rectilinearly parallel to the track and while said scoop occupies any of its arcuate positions relatively 60 to said track-mounted frame.

103. In a loading machine, the combination with spaced-apart trucks mounted in tandem on a track, of a sectional frame mounted on 65 said trucks, a pivotal connection between the

sections of said frame, and means to permit lateral adjustment of one section relatively to the other and for holding said sections against relative vertical movement when one truck runs off the end of the track and the other truck remains thereon. 70

104. In a loading machine, the combination with a frame comprising a plurality of sections the intermediate section being flexible laterally relatively to the rear section and the forward section flexible vertically relatively to the intermediate section, of conveyor mechanism extending from the front portion of said frame to the rear in a general horizontal direction and longitudinally of said frame, and means for operating said conveyor mechanism throughout the range of vertical adjustments of the forward section and throughout the range of the lateral adjustments of the forward and intermediate sections relatively to the rear section. 80 85

105. In a loading machine adapted to gather and load substantially all of the loosened material in the closed end of a mine chamber on a smooth floor formed by an undercutting tool moved laterally in an arc across said chamber from one side to the other, the combination with a main frame, a supplemental frame pivotally connected to said main frame for lateral movement relatively thereto and a scoop mounted on said supplemental frame in advance thereof and having a receiving lip constructed in the form of an arc so as to adapt it to an arc-shaped face left by an undercutting tool to enable it to pick up substantially all of the loosened material in said chamber. 90 100

106. In a loading machine, a main frame in the form of a trough mounted on wheels to run on a track, a supplemental frame 105 made in the form of a conveying trough pivoted to said first named frame for lateral movement with respect thereto and forward of said first named frame and arranged to form a continuous trough passageway in the various laterally adjustable positions and conveying mechanism consisting of one or more endless belts each extending in an unbroken length from near the forward end of the forward frame to near the rearward end of the rearward frame. 110 115

107. In a loading machine, a main frame in the form of a trough mounted on wheels to run on a track, a supplemental frame made 120 in the form of a conveying trough pivoted to said first named frame for lateral adjustment with respect thereto, a scoop mounted on the forward end of the supplemental frame for vertical adjustment thereon and arranged to form a continuous trough passageway in the various laterally and vertically adjustable positions and conveying mechanism consisting of one or more endless belts each extending in an unbroken length from near the for- 125 130

ward end of the scoop to near the rearward end of the supplemental frame.

108. In a loading machine, the combination with a frame in the form of a conveyer trough mounted on wheels to run on a track, of a scoop mounted for lateral and vertical adjustment with respect to said frame, and conveying mechanism extending in an unbroken length from near the forward end of 10 said scoop to near the rear end of said trough.

109. In a loading machine adapted to be quickly moved from one mine chamber to another in a mine, the combination with a channel mounted on wheels to run on a track, a 15 scoop connected to the forward end of said chute in position to gather substantially all of the dislodged material at the head of a mine chamber that is dislodged in one mining operation, means comprising flexible connections 20 to anchorages to move said channel and said scoop rectilinearly parallel with said track to effect reciprocation of said scoop to gather such dislodged material from positions adjacent the unmined mass in a mine chamber, 25 and means for conveying the gathered material to said chute toward loading position when said reciprocating means remains connected to predetermined anchorages until substantially all of the material dislodged by one 30 mining operation has been loaded.

110. In a loading machine adapted to be quickly moved from one mine chamber to another in a mine, the combination with a channel mounted on wheels to run on a track in a 35 mine chamber toward a mine heading from which the material is dislodged by a successive series of mining operations, of a scoop mounted at the forward end of said channel in position to gather material dislodged from 40 the mine heading in advance of said track, means comprising free predetermined anchorages for reciprocating said scoop over a sufficient range to gather all of the material dislodged at the mine heading by a plurality 45 of mining operations successively performed, and conveying mechanism for transferring toward loading position from said scoop to said channel the dislodged material from successive mining operations without extending 50 said track for any of the gathering operations.

111. In a loading machine, the combination with a frame comprising a pair of channel-shaped sections having their adjacent ends 55 pivotally connected with one another for relative lateral movement and arranged to form a continuous channel with the floor thereof extending in substantially the same horizontal plane throughout its entire length, wheels 60 connected with the outer sides of said channel-shaped sections for supporting said frame so that the floor of said sections will be in close proximity to the surface of which said machine operates and below the axes of said 65 wheels, and gathering mechanism connected

to the forward end of the forward section to gather material and direct it into the forward section.

112. A loading machine comprising two sections pivotally connected to swing laterally relatively to one another, separate sets of truck wheels for each of said sections, a scoop extending forwardly beyond the forward section, and means for supporting the rear end of the forward section on the forward end of 75 the rear section when the forward set of truck wheels is run off the mine track to permit operation of said scoop beyond the forward end of said track while the rear set of truck wheels remains on the track.

113. In a loading machine, the combination with a frame having a laterally swinging portion thereon, of a receiver for material movably connected with said laterally swinging 80 portion, a set of truck wheels for supporting 85 said laterally swinging portion on a mine track, means for moving said receiver into contact with the surface from which material is to be loaded, and means for supporting the said swinging portion when said set of wheels 90 is run off the forward end of the track and said receiver is in contact with said surface.

114. A loading machine comprising a supporting frame having a channel along which material may be moved, a scoop at the forward end of said channel and a chain conveyor extending from said scoop along said channel and having links pivotally connected together on upright axes to adapt the same to be moved with said scoop under the material and in direct contact therewith for 95 loading purposes.

115. A loading machine comprising a channel, a scoop at the forward end of said channel, a pair of chain conveyors each having 100 links pivoted together on upright axes and each extending to the forward portion of said scoop for movement therewith under and in direct contact with the loose material to be loaded, and means for driving said chain conveyors to move rearwardly along said channel the material gathered by said scoop.

116. In a loading machine, the combination with material-handling mechanism comprising gathering means adapted to move over a mine floor along horizontal lines in advance of a mine track, of truck mechanism for supporting said material-handling mechanism for transportation on said mine track, and means for supporting the forward portion 115 of said truck mechanism from said material-handling mechanism off the forward end of said track but in position to move back onto the track when the whole truck mechanism is moved rearwardly.

117. In a loading machine, the combination with material-handling mechanism comprising gathering means elongated horizontally for movement over a mine floor along horizontal lines, of a pair of trucks for supporting 120 125

said material-handling mechanism on a mine track, and connections between said trucks and between the forward truck and said material-handling mechanism for supporting said forward truck off the forward end of the track and up off the ground in position to run back onto the track when said material-handling mechanism is moved rearwardly.

118. In a loading machine, the combination with material-handling mechanism comprising a forwardly extending frame adapted to move over a surface of a floor in advance of a mine track, of a truck for supporting said material-handling mechanism on such mine track and for swinging movements about a horizontal axis, means for swinging said frame about said axis and holding said frame in elevated position during transportation along said mine track, means for moving said frame over the floor when in lowered position, and means for supporting the forward portion of said truck with its wheels beyond the forward end of said track and above the said floor.
119. In a loading machine, the combination with material-handling mechanism, of two spaced-apart trucks for supporting said material-handling mechanism on a mine track, a receiver extending forwardly from said material-handling mechanism in position to move over a mine floor in advance of said track, and connections between said trucks for supporting the forward truck beyond the forward end of said track and up off the floor in position to run back on the track when said material-handling mechanism is moved rearwardly.

120. In a loading machine, the combination with a pair of spaced-apart trucks adapted to travel on a mine track, of material-handling mechanism supported by said trucks and provided with a receiving portion adapted to rest on the surface in advance of the mine track approximately in the plane of the surface on which the track ties are laid, and connections between the forward truck and the rear truck and between the forward truck and said receiving portion to support the forward truck up off the surface in advance of said track in position to run back onto the track.

121. In a loading machine, the combination with a pair of trucks adapted to travel on a mine track, of material-handling mechanism mounted on said trucks, and means for supporting the forward truck in advance of the track and out of contact therewith but in position to run back onto said track when the material-handling mechanism is moved rearwardly.

122. In a loading machine, the combination with a pair of trucks adapted to travel on a mine track, of material-handling mechanism comprising gathering means adapted to operate over the ground surface in advance

of said track, and means for supporting the forward truck beyond the forward end of said track and clear of said ground surface in position for movement directly back onto said track.

123. In a loading machine, the combination with a pair of trucks adapted to travel on a mine track, of material-handling mechanism comprising gathering means movable over the ground surface in advance of said track, means for operating said gathering means, and mechanism for supporting the forward truck to extend beyond the forward end of said track during the operation of said gathering means and in position for movement back onto said track upon retraction of said gathering means.

124. In a loading machine, the combination with material-handling mechanism comprising forwardly extending gathering means having a receiving frame, of a truck for supporting said material-handling mechanism, means for shifting said gathering means laterally relatively to said truck and connections between the forward end of said truck and said receiving frame for supporting the forward end of said truck on said receiving frame and for preventing tilting of the truck when said frame is shifted laterally.

125. In a loading machine, the combination with a conveyor comprising a frame adapted to extend to the floor, of a scoop conveyor extension connected to said frame and adapted to move over the floor from which loose material is to be gathered and loaded, and connections between said extension and said frame for permitting adjustment of said extension relatively to said frame for scooping material from different directions and directing such material to said first-named conveyor.

126. In a loading machine, the combination with material-handling mechanism comprising gathering means adapted to operate in advance of a track on which the machine is mounted to gather material from the floor in advance of such track, of truck mechanism for supporting said material-handling mechanism on such track, and auxiliary mechanism connected to said truck mechanism to support part of the latter on the floor in advance of the track to extend the range of operations of said material-handling mechanism beyond the forward end of said mine track.

127. A loading machine comprising a pair of pivotally connected frame plates, vertical side plates connected with said frame plates, conveyor bed plates arranged above said frame plates and extending between said side plates, the side plates and bed plate for one of said frame plates being arranged to overlap the side plates and bed plate of the other of said frame plates adjacent the pivotal connection between said frame plates, and

separate endless conveyers arranged to travel upon said bed plates to transfer material between said side plates.

128. A loading machine comprising a conveyer, a scoop at the forward end of said conveyer and having a downwardly projecting portion adapted to rest on and move over the surface from which the material is to be gathered and to assist in supporting the conveyer above such surface, a rear support for the conveyer, an intermediate support for the conveyer, means associated with the intermediate support for adjusting the elevation of said downwardly projecting portion, and means for moving the scoop into the material to be loaded by said conveyer.

129. A loading machine for low roof mine chambers comprising a conveyer frame having a runway extending longitudinally thereof of along horizontal lines toward loading position, wheels at opposite sides of said runway for supporting said conveyer frame in a relatively low position, a motor mounted at one side of the runway, and power transmitting gearing between said motor and the said wheels propelling the latter to move said runway longitudinally, said gearing comprising a transverse connection extending across the conveyer frame while maintaining free passage for material along said runway along horizontal lines toward loading position.

130. In a loading machine, the combination with supporting framework, of conveyer mechanism mounted thereon, a gathering device at the forward end of said conveyer mechanism and adapted to slide over the operating surface, a plurality of supporting wheels, a plurality of swinging arms pivoted to said framework and carrying said wheels, and means for swinging said arms relatively to said framework to adjust the positions of said wheels from the surface on which they travel to an elevated position out of contact with such surface while said gathering device slides over its operating surface.

131. In a loading machine, the combination with supporting framework, of a truck for the rear portion thereof, conveyer mechanism mounted on said framework and having a receiving end at the forward end thereof, an additional truck for the forward portion of said framework back of said receiving end, and means associated with last-named truck for adjusting the elevation of said receiving end.

132. In a loading machine, the combination with a supporting frame, of propelling mechanism therefor, a supplemental frame mounted thereon to swing laterally relatively thereto, a bevel edged nose-piece at the forward end of said frame in position to rest on the floor and slide thereover to gather a load and direct it onto said supplemental frame when said propelling mechanism is

operated, and a multiple chain conveyer on said supplemental frame and comprising a plurality of spaced-apart chain conveyers operating in spaced-apart guiding grooves in upright planes to move toward loading position the material gathered onto said supplemental frame.

133. In a loading machine, the combination with a truck adapted to travel on a mine track, of a supporting frame mounted thereon and having an elongated portion extending horizontally from the truck into position to extend beyond the mine track, a traveling conveyer extending along said frame to the forward end thereof, a gathering scoop on the forward end of said elongated portion, means for operating the scoop by imparting rectilinear movement thereto parallel to the track, and wheel-supporting mechanism for the said elongated portion during transportation on said mine track but adapted to extend beyond the track when said scoop operates along various advanced positions and while said truck remains on said mine track.

134. In a loading machine adapted to be operated to load coal in advance of a mine track in a mine chamber, the combination with a main frame, of a supplemental frame pivotally connected to said main frame for lateral movement, a scoop at the forward end of said supplemental frame to extend in advance thereof and in advance of the mine track, means for reciprocating said scoop to reach forward beyond the mine track for loads in various arcuate positions, a chute back of said scoop and in alinement therewith in a general horizontal direction extending along said track, and traveling conveyer mechanism for transferring the material in said scoop rearwardly into said chute and horizontally along the latter toward the rear end thereof.

135. In a loading machine, the combination with a main frame mounted on wheels adapted to travel on a mine track, of a supplemental frame pivotally connected to said main frame for lateral movement relatively thereto, a scoop connected to said supplemental frame and movable laterally therewith, a chute back of said scoop and in alinement therewith and extending horizontally and longitudinally of said main frame from the front toward the rear thereof parallel to said mine track, propelling mechanism for said frames to force said scoop into material to be loaded, and endless conveyer mechanism traveling along said scoop relatively thereto for transferring material out of said scoop into said chute and along the latter toward loading position.

136. In a loading machine, the combination with a supporting frame, of a channel extending longitudinally thereof with its forward receiving end and its rear delivery end open with a space between the forward re-

- ceiving end and the base of the mine wall free and unobstructed for the passage of material to be loaded directly from the base of the mine wall into the receiving end of said channel, the bottom of said channel being located adjacent the supporting surface over which said machine operates and lying in the same horizontal plane throughout its length, means for supporting said frame and said channel 5 with the bottom of the latter in such position for passage of the material from the base of the mine wall along said channel in a general horizontal direction to the delivery end of said channel, and endless conveyer 10 mechanism extending from the forward receiving end of said channel to the rear delivery end thereof.
137. In a loading machine, the combination with framework comprising a longitudinal channel for passage of material to be loaded, of means comprising endless conveyer mechanism for transferring material horizontally along said channel parallel to the mine track on which the machine is 15 mounted, and supporting wheels for said framework located on opposite sides of said channel, the axes of said wheels being located approximately at the bottom of said channel.
138. In a loading machine, the combination with supporting framework, of supporting wheels on opposite sides thereof, a conduit for material to be loaded extending between said wheels and having the bottom thereof located approximately at the axes 20 of said wheels throughout the entire length of said conduit, said framework being free and unobstructed in the space between the forward receiving opening of said conduit and the base of an upright mine wall to permit movement of material directly from such mine wall base in a general horizontal direction into the receiving opening of said conduit, and endless traveling conveyer mechanism extending along the bottom of said conduit. 25
139. A machine for loading material in a mine chamber comprising framework having a passageway extending longitudinally thereof with a space between the receiving end of 30 said passageway and the upright face of a mine wall free and unobstructed, the floor of said passageway being on substantially the same level throughout its entire length and located adjacent the floor of a mine chamber, the forward end of the said floor of the passageway being in position to permit movement of material from the floor at the base 35 of the mine wall into the passageway, and endless traveling conveyer mechanism for effecting the transfer of material along said passageway adjacent the floor of the mine chamber and discharged from the rear end 40 of said passageway into a transporting receptacle.
140. In a loading machine the combination with a supporting frame, of a substantially horizontal elongated trough open at both ends, a scoop in alinement with the forward end of said trough and adapted to reach forward to gather material from the base of the mine wall, means for reciprocating the whole machine to effect the operation of said scoop to gather material, and endless traveling conveyer mechanism for transferring the gathered material from said scoop into said trough and horizontally along the latter toward loading position. 45
141. In a loading machine, the combination with two trucks, of means pivotally connecting said trucks for relative movement while confining them against relative upward movement, conveying mechanism extending along said trucks, and gathering mechanism in co-operative relation for movements corresponding to relative movements of the trucks while maintaining delivery communication to said conveying mechanism. 50
142. In a loading machine, the combination with material-handling apparatus comprising conveyer mechanism, of a pair of spaced-apart trucks for supporting said conveyer mechanism, a pair of spaced-apart arcuate arms extending from one of said trucks toward the other, a circular extension from the other truck in position to be embraced by said arms, and interlocking connections between said arms and said circular extension to confine relative movements of said trucks to general horizontal directions on an upright axis while delivery communication between the forward portion of the conveyer mechanism and the rear portion thereof is maintained. 55
143. In a loading machine, the combination with material-handling mechanism comprising gathering means adapted to rest on the floor of a mine chamber in advance of a mine track, of truck mechanism for supporting said material-handling mechanism on said track, and means between said truck mechanism and said gathering means to support part of said truck mechanism on said floor. 60
144. In a loading machine, the combination with material-handling mechanism, having a floor support adapted to rest on and move along horizontal lines over a mine floor in advance of a mine track, of truck mechanism for supporting said material-handling mechanism, said floor support being connected to the forward portion of said truck mechanism, and means for adjusting the position of said support relative to the forward portion of said truck mechanism to cause said support to ride over the floor and sustain the forward portion of the truck mechanism while the latter moves off the forward end of the mine track. 65
145. In a loading machine, the combination with a truck adapted to travel on a mine

track, of a conveyer mounted on said truck and extending in advance thereof, means for adjusting the forward end portion of said conveyer relative to said truck to support said conveyer clear of said track during transportation along said track and for adjusting said forward end portion downwardly for movement over a mine floor in advance of said track, a floor support connected to said conveyer and to said truck to transfer a portion of the weight of said truck to said support independently of said track to hold the truck off the ground in advance of the track and in position for movement back onto said track.

146. In a loading machine, the combination with two trucks pivotally connected for relative movement about an upright axis, of material-handling mechanism supported on said trucks and comprising jointed portions for lateral flexibility of the material-handling mechanism on an upright axis, means for swinging the forward end of the material-handling mechanism up and down on a horizontal axis, and means for supporting the forward truck in advance of the mine track on which it is adapted to run, in position to clear the floor surface in advance of said track and to run directly back onto said track upon retraction of said material-handling mechanism.

147. In a loading machine, the combination with a pair of spaced-apart trucks, of material-handling mechanism supported by said trucks and jointed between the latter for lateral flexibility on an upright axis while said trucks are on a curved mine track, and interlocking connections between said trucks to confine relative movements between them to general horizontal directions on said upright axis while maintaining delivery communication through the material-handling mechanism at said joint.

148. In a loading machine, the combination with material-handling mechanism, of a pair of trucks for carrying said material-handling mechanism, said trucks being arranged one in front of the other and spaced-apart for travel along a mine track, a flexible joint between the trucks and between the forward and rear portions of said material-handling mechanism, said joint affording flexibility of horizontal lateral movement about an upright axis of said trucks relatively to each other and of the forward and rear portions of said material-handling mechanism relatively to each other, and means for locking the trucks in adjusted position against movement about said upright axis.

In testimony whereof I have signed my name to this specification on this 4th day of December, A. D. 1917.

EDMUND C. MORGAN.
